DESIGN.

T. ONSLOW.

CARPET.

No. 15,276.

Patented Aug. 19, 1884.

FLUMO KNIGHT
PATTERNS

UNITED STATES PATENT OFFICE.

THOMAS ONSLOW, OF PHILADELPHIA, PENNSYLVANIA, ASSIGNOR TO ROWLAND & SCHMIDT, OF SAME PLACE.

DESIGN FOR A CARPET.

SPECIFICATION forming part of Design No. 15,276, dated August 19, 1884.

Application filed July 12, 1884. Term of patent 3½ years.

To all whom it may concern:

Be it known that I, THOMAS ONSLOW, of Philadelphia, Pennsylvania, have invented and produced a new and original Design for 5 Carpets, of which the following is a specification.

The nature of my design is fully represented in the accompanying photographic illustration, to which reference is made.

I claim as my invention—

The design for a carpet, as shown.

Witnesses: THOMAS ONSLOW,

WM. O. ROWLAND,

JOHN T. THOMPSON.
